(57) **CLAIM**

I claim, the ornamental design for a cap, as shown and described.

DESCRIPTION

FIG. 1 is a front elevational view showing my new design;
FIG. 2 is a side elevational view thereof;
FIG. 3 is a top plan view shown thereof;
FIG. 4 is a front elevational view of an alternate design;
FIG. 5 is a side elevational view of the design shown in FIG. 4; and,
FIG. 6 is a top plan view shown in FIG. 4.
The features of the article shown in broken lines form no part
of the claimed design.
